UNITED STATES PATENT OFFICE

CORREL D. POTTER, OF ADAMS CENTRE, NEW YORK.

DESIGN FOR INKSTANDS.

Specification forming part of Design No. **11,439**, dated September 30, 1879; application filed July 28, 1879.
[Term of patent 14 years.]

To all whom it may concern:

Be it known that I, CORREL D. POTTER, of Adams Centre, Jefferson county, and State of New York, have originated and Designed a Pattern for Ink-Bottles, of which the following is a full, clear, and exact description, reference being had to the accompanying drawing, making part of this specification.

The bottle is cubical in form. Each side 1 and the top 2 of the bottle form raised panels. The vertical corners 3 3 3 and the horizontal top corners 4 4 are rounded, as shown in the drawing.

What I claim as my invention is—

A design for ink-bottles, consisting of the cubically-formed body provided with the raised side panels, 1 1, top panel, 2, and the rounded corners 3 3 3 and 4 4, substantially as shown and described.

C. D. POTTER.
